UNITED STATES PATENT OFFICE

SAMUEL P. COULTER, OF MUNCIE, INDIANA

WATER TUBE BOILER

Application filed March 28, 1928. Serial No. 265,370.

The object of the invention is to provide a boiler of the water tube style which is of such a form that it may be constructed in units having high horse-power ratings and 5 practically wholly of boiler steel so as to avoid the use of brick construction in the insulation thereof; to provide a boiler of this character in which the shell is of such form that for a given size a maximum of heating 10 surface is presented to the action of the furnace gases; to provide a construction in which the shell houses the furnace as well as the water circulating tubes; and to provide a construction in which the walls defining the furnace as well as those for deflecting the exhaust gases in their passage 15 to the smoke-box are of hollow form and constitute water circulating mediums.

With this object in view the invention consists in a construction and combination of parts of which an acceptable embodiment is described in the following specification and illustrated in the accompanying drawings wherein:

25 Figure 1 is a central vertical longitudinal sectional view of a boiler construction in accordance with the invention.

Figure 2 is a front elevational view.

Figure 3 is a view partly in end elevation 30 and partly in vertical section of the shell of the boiler, and

Figure 4 is a vertical sectional view of a portion of the shell of the boiler.

The shell 10 which houses the water circulating tubes 11 as well as the furnace 12 is of U-shaped form, being constructed of boiler sheet shaped to provide a transversely arcuate drum 14 and lateral pendant water legs 15. The sheets constituting the shell are united in any acceptable manner but are shown in the illustrated embodiment as riveted, as indicated at 16, the drum, to preserve its shape under pressure, being stayed as indicated at 17 and the water legs stayed as indicated at 17a.

The boiler front, below the drum, is defined by a series of transverse headers 18 arranged in superposed relation and a furnace door ring 19. The headers and door ring are preferably of cast steel and of hol-

low form. They span the water legs 15 at the front and are in communication with the latter by means of nipples 20. The door ring is formed with door openings 21 and 22 giving access to the fire-box and ash pit 55 respectively of the furnace 12.

The tubes 11 connect with the headers 18 and open into the latter and they likewise connect with and open into the headers 23 disposed at the rear end of the shell but 60 spanning the water legs and being interiorly in communication with the latter by means of nipples 24. The headers 23 are identical with the headers 18 and arranged in the same manner but at a lower level than the headers 18 to give a downward inclination 65 rearwardly to the tubes 11. The headers being of cross-sectionally rectangular form and the tubes being disposed at right angle to the connected walls of the headers, the latter are disposed at a slight angle to the perpendicular and this arrangement disposes the rear lower edge of each header below the horizontal plane of the outer upper edge of the next lower header, thus providing for an overlap of the adjacent 70 headers. This arrangement facilitates the assembling operation as the headers may be first placed with front walls vertical when there is enough space between adjacent 75 headers to provide for mounting of each one without interference from the adjacent one. After mounting, the swinging of the headers to the inclined positions, which are those that must be assumed when the tubes are 80 installed, brings the walls of adjacent headers into relatively close arrangement.

The back wall 25 of the furnace 12 is in the form of a hollow steel casting spanning 85 the water legs 15 and acting as a circulating medium for the boiler water by reason of the nipple connections 26 with the water legs. Set upon the back wall is a baffle 27 which extends to the top row of tubes 11. This baffle may be of any acceptable material, 90 preferably brick. A hollow baffle plate 28 spans the water legs 15 just below the drum 14, this baffle plate being disposed in a vertical plane intermediate between the vertical 95 planes of the back wall 25 and the rear end 100.

of the shell. It is preferably a hollow steel casting and constitutes a water circulating medium by reason of its nipple connections 29 with the water legs 15. A baffle 30 preferably of brick extends from the lower edge 5 of the baffle plate 28 to the bottom row of the tubes 11.

The rear end of the shell below the headers 23 and between the water legs 15 is closed 10 with a wall 31 and above the headers is provided with a thimble 32 for connection with the stack to place the smoke-box 33 in connection with the latter.

The fire laid on the grate 34 heats directly 15 the adjacent portions of the shell and water circulating parts, the burnt gases arising passing between the tubes 11 forward of the baffle 27, down between the tubes back of baffle 27, down under the under edge of the 20 baffle 30 and up between the tubes into the smoke-box 33 and thence to the stack.

A fusible plug 35 is mounted in the crown sheet 36 just above the furnace 12.

To give ready access to the tubes 11 both 25 the headers 18 and 23 are provided with hand openings 37 arranged in axial coincidence with the tubes, each hand hole being inclosed with a removable cover plate not shown.

30 By reason of the particular form of shell and arrangement of water circulating tubes in the latter a maximum heating surface is presented to the action of the heat given off by the furnace, so that for a unit of given dimensions, a maximum amount of water is 35 evaporated resulting in increased steam output, thereby increasing the steam generating capacity without increasing the physical dimensions. The particular form of door ring 40 and baffle plate add to the steam generating properties and the form generally makes for the installation without the use of brick-work except where it may be desired to use it, instead of metal, on top of the back wall 45 and below the baffle plate.

45 From the foregoing description, taken in connection with the accompanying drawings, it will be noted that the headers of each set are free of communication and connection 50 with each other, that the hollow front or door ring is free of communication and connection with the headers, that the back wall is located below the tubes, that the baffle is located above the tubes, and that the headers, front wall, back wall and baffle are 55 connected to the water legs solely by the nipples which establish communication between said parts, with the result that any or all of the parts may be easily and quickly 60 removed and replaced.

The invention having been described, what is claimed as new and useful is:

65 A steam generator, comprising a drum, water legs co-extensive with the drum and disposed at opposite sides thereof, front and

rear sets of headers spanning the water legs, the headers of each set being free of communication and connection with each other, nipples establishing communication between the water legs and the ends of the headers 70 and constituting the sole means for connecting the headers to the water legs, one set of headers being disposed at a lower level than the other set and the headers of both sets being cross-sectionally angular in form and disposed at a slight angle to the perpendicular with the rear lower edge of each header below the horizontal plane of the front upper edge of the next lower header, tubes 75 connecting the headers, a hollow cast steel front spanning the water legs below the front headers and having fire and ash door openings and connected to the water legs and free of communication and connection with the headers, a hollow back wall spanning 80 the water legs below the tubes and communicating with the water legs, and a hollow baffle spanning the water legs above the tubes and communicating with the water legs.

In testimony whereof he affixes his signature.

SAMUEL P. COULTER.
